TELEVISION APPARATUS

Lee de Forest, Hollywood, Calif., assignor to
American Television Laboratories, Inc., a cor-
poration of Delaware

Original application April 24, 1931, Serial No.
532,454, now Patent No. 2,026,872 dated Jan-
uary 7, 1936. Divided and this application Sep-
tember 5, 1931, Serial No. 561,512

10 Claims. (Cl. 178—6)

This application is a division of application Serial No. 532,454, filed April 24, 1931, and has to do in a general way with the art of television, being more particularly related to an improved 5 apparatus for receiving and reproducing televised pictures and images.

It is well known to those familiar with the art that images can be converted into electrical impulse modulations which may be transmitted 10 by radio or by wire and received at distant points, where, through the medium of so-called television receiving apparatus they can be converted into images corresponding to the transmitted images. The reproduction of the images at the receiving station is generally accomplished by 15 means of a pulsating neon light associated with a scanning disk, and since the quantity of such light available is very small, the reproduced image is dim and is incapable of satisfactory magnification. It, therefore, becomes a primary object of this invention to produce an apparatus of 20 the class described whereby the televised image may be reproduced with light of sufficient intensity to permit its magnification.

Pursuant to the attainment of this object the present invention contemplates the use of a novel type of scanning disk which may be used with a source of light of high intensity and is provided with light valves adapted to be controlled by 25 impulses from a television receiver for governing the quantity of light passing from the source through the successive aperture of the scanning disk. Through the medium of this apparatus I am able to reproduce the televised image with a 30 much brighter light which may be magnified so as to produce a sharp image of much greater proportions than has heretofore been possible.

The construction of a preferred embodiment of my invention, together with other objects attending its production, will be best understood 40 from the following description of the accompanying drawings which are chosen for illustrative purposes only, and in which—

Fig. 1 is an elevational view showing an improved type of scanning disk contemplated by this invention;

Fig. 2 is an end elevation illustrating the manner of utilizing the scanning disk shown in Fig. 1;

Fig. 3 is an elevational view similar to Fig. 2, 50 showing a modified form of scanning disk;

Fig. 4 is an elevational view illustrating a modified form of Kerr cell construction which may be employed in the device contemplated by this invention;

Fig. 5 is a sectional view which may be con-

sidered as having been taken in a plane represented by the line 5—5 in Fig. 4;

Fig. 6 is a sectional view illustrating the manner of mounting the cell construction shown in Fig. 5 upon a scanning disk;

Fig. 7 is an enlarged sectional view showing the details in the construction of a preferred form of individual Kerr cell adapted for use in connection with this invention;

Fig. 8 is a sectional view which may be con- 10 sidered as having been taken in a plane represented by the line 8—8 in Fig. 7.

As pointed out above, the method involved in the present invention is one in which the image is produced directly by means of an apertured 15 scanning disk of the usual type, which is provided with novel means adapting the same to use with a constant light source of high intensity. The apparatus employed, as illustrated in the drawings, consists in a general way of a light source and a scanning disk of the conventional Nipkow type which are associated with means for modulating or valving a bright beam or area of light by means of a succession of rapidly moving light valves which are preferably arranged in 20 spiral relation upon the scanning disk.

In Fig. 1 the rectangle A represents a small intensely brightly illuminated area on the back side of a scanning disk 110 which is made of non-conducting material. The light thrown on A 30 comes preferably from an intense source of light shown in Fig. 2 as an arc 111 behind which is a reflector 112 and in front of which is a condensing lens 113. This source of light and lens are so arranged as to throw on a Nicol prism 114 a 35 beam of light which is limited to the desired square area by means of an opaque frame 115.

A succession of apertures 116 preferably round in form, is arranged in the usual spiral form piercing the non-conducting scanning disk 110, as 40 clearly shown in Fig. 1. Behind each aperture is placed a small Kerr cell 117 in such a manner that the portion of the light of the brightly illuminated area A which passes through a given aperture 116 must also pass through the individual 45 Kerr cell located directly in front of said aperture.

One armature of each Kerr cell is connected by means of the suitable conductor 119 to a corresponding segment 120 of a commutator 121 50 which is arranged around a shaft 122 which carries the disk. The several commutator segments are so dimensioned and spaced and a brush 123 is so placed that only the active armature of the Kerr cell which is at that moment traversing the 55

illuminated area A is connected in the electric circuit. The other armature of each of the Kerr cells is connected to a common conductor 124. This common or bus conductor is connected 5 through a conductor 124' to the metal shaft 122 which carries the scanning disk 110. The brush 123 and shaft 122 are connected through conductors 125 and 126 to the output terminals of the secondary 127 of a transformer 128. Inserted 10 in series in this secondary circuit are high voltage polarizing batteries 129, the purpose of which is to impress across the armature of whichever Kerr cell happens to be in circuit a constant high voltage polarizing potential. The output of a 15 television receiver amplifier (not shown) is led to the terminals of the primary 130 of the transformer 128. By the above described arrangement, which is the usual circuit arrangement for modulating or valving light transmitted through 20 a Kerr cell by means of received alternating current energy, as employed in talking picture recording and in certain previously known television receiving systems, I am able to modulate, or valve, the light which is passing through a given 25 aperture on the scanning disk, because as is well known, the action of the Kerr cell is to elliptically polarize the beam of light, which, from practical considerations, is the equivalent of rotating through a greater or less angle the plane of 30 polarization of a polarized light beam passed therethrough.

As shown in Fig. 2, I provide in front of the scanning disk and directly opposite the polarizing Nicol prism 114, the analyzing prism 114a whose 35 axis is turned through 90° relative to the angle of the first. In front of this second prism at a suitable distance I place a projecting lens 131 by means of which the small image which passes through the prism 114a is enlarged and thrown 40 upon a screen 132, so that the enlarged image is seen, preferably by reversed projection, by the eye of the observer at 133.

The arrangement I have just described possesses many advantages over the heretofore 45 used devices for television projecting wherein a single Kerr cell is employed to valve the concentrated light from a powerful arc lamp, and said valved light beam thereafter being distributed over the screen by means of a scanning disk 50 containing lenses arranged in spiraled relationship. For example, by my method only a small portion of the light passes through any one Kerr cell, by virtue of which the cell is not subjected to 55 damaging heat. Moreover, the cells are kept in very rapid motion and thereby very effectively air-cooled. Furthermore, the Nicol prisms are not subjected to the intense heat of a point of concentrated arc beam, as is the case where a single Kerr cell and small Nicol prisms are employed.

Fig. 2 shows the synchronized motor 135 driving by means of the speed-multiplying gears 136-137 the shaft carrying the scanning disk 110 and commutator 121. The shaft and circuit 60 are shown grounded at E, (Fig. 5).

138 shows the 3 leads to the conventional three phase motor 135. I have shown no detailed means for synchronizing the scanning disk at the receiver with that at the distant transmitting 70 station, inasmuch as I synchronize my receiver by any one of the well known and effective synchronizing systems, and as this forms no part of my present invention it is unnecessary to go into detail regarding same at this time.

75 Fig. 3 shows a somewhat improved method of

using the Kerr cell and commutator, whereby troubles of contact commutation between a fixed brush and rapidly moving commutator segments are avoided. In the arrangement shown in this figure the individual Kerr cells 5 117' are arranged in spiral relationship as before, with the one armature of each connected to the common bus bar 124' which is connected, preferably by means of four conductors 140, 90 degrees apart, to the shaft 122' of the scanning 10 disk 110', thence through the conductor to one terminal of the polarizing battery 129' and preferably grounded. The other terminal of this polarizing battery is led through the secondary 127' of the transformer 128', as described in 15 connection with this same circuit as shown in Fig. 1 and thence through the conductor 125' to the insulated plate 141.

Around the circular periphery of the scanning disk 110' is arranged a series of conducting 20 plates 142 of considerable area. The outer surfaces of these plates are turned to conform with the curvature of the scanning disk, and fixed plate 141, similarly curved, is so arranged as to come in very close proximity to, but not quite in 25 contact with the sectors 142. Each sector 142 is then connected by means of a wire 143 to the insulated armature of its appropriate Kerr cell, (117') as is clearly shown in Fig. 3. Inasmuch as the capacity of the condenser formed between 30 fixed plate 141 and any individual moving armature plate 142 on the periphery of the scanning disk is thus made large compared with the capacity of any individual Kerr cell the electrical 35 action across the Kerr cell which is thus put into circuit is essentially the same as that shown in Fig. 1. If desired, a stopping, or safety condenser C can be inserted in the circuit of Fig. 1, as well as in that of Fig. 3, and otherwise the 40 operation of the arrangement shown in Fig. 3 is identically the same as that above described in connection with Fig. 1.

As a further modification of this arrangement of a multiplicity of Kerr cells in spiral formation upon a scanning disk, I have shown in Fig. 4 a 45 single glass tube 150 arranged in the proper spiral form and carrying on its inner shorter face a common conductor, or armature, 151. Opposite this conductor and at an appropriate distance therefrom, and suitably spaced relative to 50 each other, are a series of small armatures 152, a lead from each of which is brought out through the wall of the glass tube and led to its corresponding large-area plates 141'. These plates are arranged as shown in Fig. 3 about the 55 circular periphery of the scanning disk.

The common conductor 151 may be in the form of a metallic conductor deposited on the inside of the spiral formed glass tube, or may be located on the outside thereof, leaving only 60 one set of armatures of the Kerr cell inside the glass tube. This glass tube is preferably not circular in cross section, but is flattened as shown in Fig. 5, which figure shows clearly the common armature 151, in this case located outside of the 65 glass tube on its bottom surface, and an individual short armature of the Kerr cell 152 located inside of the glass tube with its lead 153 brought out through the flattened wall of the tube, sealed therethrough, and carried on to the 70 conducting plate 142'. The fixed condenser armature plate 141' is also shown in close proximity to the moving plate 142' and connected to the conductor 125a.

Inasmuch as the action of the Kerr cell to 75

equivalently rotate the plane of polarization of the light beam is more effective the closer together are the two armatures, or electrodes, of the Kerr cell, I prefer to locate the individual armature of said cell close to the flattened bottom of the glass tube. I prefer to leave a gap of say ten one-thousandths of an inch between the armature 152 and the bottom wall of the tube, or between the two metal armatures of the Kerr cell in case both armatures are placed within the glass vessel. The most suitable metal for such Kerr cells armatures I have found to be gold, or some other suitable metal gold-plated. I prefer to use as my light rotating liquid in the Kerr cell a solution of nitro-benzol.

Fig. 6 shows how the spiral formed glass vessel containing the multiplicity of Kerr cells is attached to one face of the insulating scanning disk. The glass tube is supported on the metal bracket 160 which is fastened by suitable means to one side of the scanning disk 110a. This figure shows a small aperture 161 drilled through the face of the scanning disk whereby a small beam of light is permitted to pass through the Kerr cell after having traversed the polarizing Nicol prism 214. Having traversed the space between the armatures of the Kerr cell and having its plane of polarization more or less rotated by such passage the beam of light is shown thence passing through the analyzing Nicol prism 214a.

In Fig. 7, I have shown one form of small individual Kerr cell consisting of an elongated glass capsule 165 containing two metal armatures 117a—118a, suitably separated, each with its lead brought out through an opposite end of the capsule, as shown by 119' and 124a. Reference numeral 166 indicates the extension of the glass envelope, whereby the Kerr cell is filled with nitro-benzol solution and then sealed off. These individual Kerr cells are then mounted in proper relationship around the scanning disk and the armature is connected respectively to the common conductor and to the individual commutator leads as described in connection with Fig. 1 or Fig. 3.

Fig. 8 shows a sectional view of one of these individual Kerr cells taken at right angles to the view shown in Fig. 7. It is here seen that the passage of the beam of light, indicated by arrow B, is through the small diameter of the glass envelope, and between the two armature plates of the cell. I so place these individual Kerr cells that the prolongation 166 is pointed towards the center of the scanning disk so that when the disk is in rapid rotation centrifugal force causes the fluid to completely fill the space between and surrounding the two armatures of the cell, leaving the air bubble (which is usually present after sealing off the glass capsule) in the prolongation 60 of the capsule.

Many other modifications and changes in details will occur to those skilled in the art without departing from the spirit and scope of my invention as defined in the appended claims; but having now set forth the object and nature of my invention and having shown and described structures embodying the principles thereof and illustrating the method employed in accordance therewith, what I claim as new and useful and 70 of my own invention and desire to secure by Letters Patent, is:

I claim as my invention:

1. For use in a television receiver: a scanning disk provided with a multiplicity of apertures; a Kerr cell at each of said apertures; means for ro-

tating said scanning disk; and means for electrically charging the successive Kerr cells from a television receiver during the rotation of said disk.

2. For use in a television receiver: a scanning disk provided with a multiplicity of apertures; a Kerr cell at each of said apertures; a commutator on said scanning disk; means for connecting one armature of each Kerr cell to one segment of said commutator; a common conductor on said scanning disk; means for connecting the other armature of each Kerr cell to said common conductor; and means for connecting the common conductor and the successive segments of said commutator to the output of a television receiver. 15

3. For use in a television receiver: a scanning disk provided with a multiplicity of apertures; a Kerr cell at each of said apertures; a series of commutator segments on the periphery of said disk; means connecting one armature of each Kerr cell to one of said commutator segments; a common conductor on said disk; means for connecting the other armature of each Kerr cell to said common conductor; and means for connecting the successive commutator segments and the 25 said common conductor to the output of a television receiver.

4. For use in a television receiver: a scanning device embodying; a scanning disk provided with a multiplicity of apertures arranged in a spiral 30 path; a transparent tube containing a polarizing fluid mounted on said disk opposite the apertures therein; means for rotating said scanning disk; means for projecting a beam of polarized light toward said disk and over an area traversed by 35 said apertures; a plurality of armatures on opposite sides of said tube adjacent said apertures; means for connecting said armatures with the output of a television receiver during the movement of said aperture through the illuminated 40 area; and an analyzing prism for passing the light coming from said apertures.

5. For use in a television receiver: a scanning device embodying; a scanning disk provided with a multiplicity of apertures arranged in a spiral 45 path; a Kerr cell mounted on said disk at each aperture; means for rotating said scanning disk; means for illuminating an area of said disk traversed by said apertures with a beam of polarized light; means for energizing each Kerr cell during 50 its movement through the illuminated area from a television receiver; and an analyzing prism for passing the light coming from the successive Kerr cells.

6. For use in a television receiver: a scanning 55 disk provided with a multiplicity of spirally arranged apertures; means for rotating said disk; a spiral tube filled with polarizing fluid mounted on said disk opposite said apertures; armatures on opposite sides of said tube adjacent said 60 apertures; and means for connecting said armatures with the output of a television receiver during the movement of said apertures through a predetermined area.

7. In combination a rotatable scanning member provided with a plurality of scanning apertures, a Kerr cell for each aperture, a commutator, means connecting one armature of each Kerr cell to a corresponding segment of said commutator, a common conductor, means connecting 70 the other armature of each Kerr cell to said common conductor, and means connecting the current conductor and the segments of said commutator successively to the output of a television receiver. 75

8. In combination a rotatable perforated scanner having a plurality of scanning apertures and a plurality of sets of Kerr cell electrodes carried by said member, there being one set of electrodes adjacent each of said apertures, and a polarizing medium between each set of electrodes.

9. The combination according to claim 8, in

which all the said sets of electrodes are mounted within a single enclosing envelope.

10. The combination according to claim 8, in which the said sets of electrodes are mounted within a common spiral enclosing envelope containing a solution of nitro-benzol.

LEEE DE FOREST.
